UNITED STATES PATENT OFFICE

DOMINGO ANGLADA, OF NEW YORK, N. Y., ASSIGNOR TO WOLF SAFETY LAMP COMPANY OF AMERICA, INC., OF BROOKLYN, NEW YORK, A CORPORATION OF NEW YORK

SIGNAL LAMP

Application filed August 31, 1929. Serial No. 389,652.

This invention relates to signal lamps and is particularly useful to workmen engaged along tracks of railway and subway systems.

The object of the invention is intended to provide the workman with illumination, as he is engaged upon his work along the tracks, and with a rear signal light which may be changed at will from red to green or from green to red depending upon the message which the workman may wish to convey to the engineer or motorman of an approaching train.

In the embodiment of this invention and for the purpose of illustrating the same, the improvements of this invention have been embodied in a lamp as shown in the accompanying drawings.

In the drawings, Fig. 1 is a vertical sectional elevation of a complete lamp embodying the present invention;

Fig. 2 is a rear view thereof;

Fig. 3 is a horizontal section on line 2—2 of Fig. 1;

Fig. 4 is a sectional detail on line 4—4 of Fig. 1;

Fig. 5 is a side elevation of Fig. 4.

This invention, for the purpose of illustration, is shown and described as embodied in a carbide lamp of the type shown in my earlier Patent No. 1,617,432, dated February 15, 1927. The lamp consists of the carbide chamber 1, the water reservoir 2, which are secured together by the screw threaded bolt 3. The feed of the water, as is well known in such construction, from the water reservoir to the feed mechanism, is regulated by the valve 4. The gas generated in the carbide chamber passes through the burner tube 5 to the burner 6 where a flame of considerable brightness is produced while the lamp is burning. The illuminating light is projected forwardly through the lens 7 and rearwardly through the chimney 8, which passes through the water reservoir 2, to the rear of the lamp and illuminates a rear signal positioned in line therewith. At the rear of the lamp a plurality of differently colored lenses are provided, each having, according to its color, a particular significance as a signal. The user of the lamp may move

either lens into illuminating position with the light channel to provide the required signal. In railroad operations, particularly in subways, it is sufficient if the lamp is provided with red and green lens and for the purpose of illustrating this invention one of said lens is to be considered as being red and the other as green. Upon the back 9 of the water reservoir 2 a bracket 10 is suitably attached either by riveting or soldering, which bracket is provided with the outwardly extending arms 11, having the support 12 pivotally secured thereto by the screws 13 passing through aligned holes in the arms 11 and the plates 14. The plates 14 terminate in the circular lens holding frames 15 and 16, the horizontal axes of which are at substantially right angles. The green lens 17 is positioned in the frame 15 and the red lens 18 is positioned in the frame 16. These lenses are secured against displacement by suitable expansion rings 19 fitted into the respective frames. The lower arm 11 of the bracket 10 is provided with an extension 20 spaced from the lower plate 14 to which is secured the U-shaped bracket 21. The locking member 22 is supported by the U-shaped bracket 21 and comprises the finger piece 23, the pin 24 passing through apertures in the underside of the bracket 21 and in the extension 20. The pin is constantly urged upward under pressure of the spring 25 which abuts against the underside of the lower cross piece of the bracket 21 and against the collar 26 secured to said pin. The lower plate 14 of the support 12 is provided with two apertures 27, 28 positioned respectively to the rear of the lens 17, 18 and engaging with the pin 24 of the locking member 22 as the said apertures are respectively aligned with said pin.

The wall 29 forming the light channel 8 is provided with an extension 30 attached by screw threads thereto. The lens frames 15, 16 are spaced from the extension 30 in order that the frames will not strike the end of the extension 30 as the lens frames are moved into alignment with the light channel.

The operator while using the lamp illu-

minates the work with the light issuing from the lens 7 and ordinarily would, while engaged upon the tracks in inspection or repair work, protect himself from an approaching train by aligning the red signal lens 18 with the light channel 8 whereby it is illuminated and warns the operator of an approaching train of the presence of the workman on the tracks. The user of the lamp, when he desires to signal that the road is clear for the train to proceed, will change the red signal to green by releasing the locking member 22 and tipping the lamp slightly to the right which will cause the lens supports to swing to the right and thereby align the green light 17 with the light channel 8. The green lens may in turn be aligned with the light channel by releasing the lock and tipping the lamp to the left. In order to automatically align the apertures 27, 28 with the pin of the lock 22, the frames 15, 16 are of such a size that their edges will abut against the body of the reservoir whereby the aperture is aligned with the pin and under the influence of the spring 25 the pin snaps into the aperture opposite thereto.

The inactive lens when it is swung out of alignment with the light channel 8, takes a position in line with the side of the extension 29 out of the range of the light stream, the sides of the extension 29 acting as a shield to blind the inactive lens.

I claim:

- 35 1. A signal lamp comprising a source of light, an illuminating outlet at the front of said lamp permitting the projection of illuminating rays from the interior of the lamp, a signal port aligned with and spaced from said outlet, a plurality of different signals arranged on the outside of said lamp near said port and adapted to be selectively moved, at will, into alignment with said port for illumination, said signals having a fixed spaced relation with respect to each other and upon movement of a signal out of alignment with said port another signal is automatically aligned, by reason of said fixed relation, with said port.
- 50 2. A signal lamp comprising a source of light, an illuminating outlet at the front of said lamp permitting the projection of illuminating rays from the interior of the lamp, a signal port aligned with and spaced from said outlet, a plurality of different signals arranged on the outside of said lamp near said port and adapted to be selectively moved, at will, into alignment with said port for illumination, said signals having a fixed spaced relation with respect to each other and upon movement of a signal out of alignment with said port another signal is automatically aligned, by reason of said fixed relation, with said port,
- 65 63 a lock for securing the signal, moved into

alignment with said port, from displacement.

3. A signal lamp, comprising a source of light, an illuminating outlet at the front of said lamp, a manually adjustable carrier secured on the outside of the body of the lamp in alignment with said illuminating outlet, a plurality of signals supported by said carrier, said signals being arranged at right angles to each other and movable at will into the path of said carrier and a lock to secure said carrier against displacement.

4. A signal lamp comprising a source of light, a single illuminating outlet at the front thereof permitting the projection of illuminating rays forwardly of said lamp, a signal port spaced rearwardly from said source of light, a carrier on the outside of said lamp, two differently colored signals supported on said carrier, said support being adapted to be moved across said port to position one of said signals in alignment with said port and to position the other signal out of alignment with the light issuing from said port.

5. A signal lamp comprising a burner adapted to provide a source of light, an illuminating outlet in the front of the lamp, a light channel directed rearwardly from the said burner and terminating in a light port in the rear of the lamp, a carrier on the outside of said lamp supported at the rear of the lamp and in proximity to said port, a plurality of frames on said carrier arranged in angular relation to each other, each frame being provided with a signal material of different significance, said carrier being adapted to move across the said port, said frames partaking of the movement of said carrier, means for limiting the movement of said carrier, a lock, said lock securing the carrier against movement while one of said signals is aligned with said port.

6. A signal lamp comprising a burner adapted to provide a source of light, an illuminating outlet in the front of said lamp, a light channel directed rearwardly from said burner and terminating in a light port at the rear of the lamp, a movable carrier on the outside of said lamp, a plurality of signals supported on said carrier, said signals being adapted to be selectively aligned with said light port and a shield to blind the signal not in alignment with said light port.

7. A signal lamp comprising a burner, an illuminating outlet in the front of the lamp, a bracket secured to the rear of the lamp, a support pivotally connected with said bracket, two lens holders having connection with said support, said lens holders being arranged at substantially right angles and being horizontally movable through an arc,
